Primary Examiner — Katherine A Holbrow

Assistant Examiner — Riya Salil Kamat

(74) Attorney, Agent, or Firm — Hawaii Patent Services;
Nathaniel K. Fedde; Kenton N. Fedde(57) **CLAIM**

The ornamental design for a belt squat machine, as shown and described.

DESCRIPTION

FIG. 1 is a front perspective view of a belt squat machine, showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a partial enlarged view of FIG. 1.

The dash-dot broken lines in FIGS. 1 and 9 show the boundary of the enlarged view and form no part of the claimed design.

1 Claim, 9 Drawing Sheets(56)
